[57] CLAIM

The ornamental design for a positive displacement diaphragm fluid meter housing, as shown and described.

DESCRIPTION

FIG. 1 is a front perspective view of a positive displacement diaphragm fluid meter housing showing my new design;

FIG. 1 is a front perspective view of a positive displacement diaphragm fluid meter housing showing my new design;

FIG. 2 is a front elevational view thereof;

FIG. 3 is a right side elevational view thereof, the opposite side being a mirror image;

FIG. 4 is a top plan view thereof;

FIG. 5 is a bottom plan view thereof; and

FIG. 6 is a rear elevational view thereof.
